CLAMPING DEVICE

Henry Stodgell, Seattle, Wash.

Application May 20, 1952, Serial No. 288,800

3 Claims. (Cl. 33—86)

1

This invention relates to a clamping means and it has reference more particularly to a pair of identical spring steel clamps to be used in combination with a chalk line to hold the ends of the taut chalk line in a fixed position and wherein the clamps are adapted primarily to be removably applied to opposite ends of a board.

A chalk line is commonly used by carpenters, bricklayers and other workmen to mark a relatively straight line of substantial length. The common practice is to drive a nail or brad into the board or object to be marked and secure one end of the line to the nail and then drive another nail in the opposite end of the board and to draw the line tight and to secure it to the second nail. The line is then chalked and the marking of the board is obtained by raising the line and releasing it so as to strike the board and deposit a portion of the chalk in a relatively straight line on the board. After the marking has thus been accomplished, it is then necessary to loosen the line and remove the nails from the board.

It is the principal object of this invention to provide a clamping device to be used in combination with a chalk line to secure its ends and which may be easily and quickly applied to boards of varying thickness without requiring the use of nails or other securing means for their securement.

Another object of this invention is to provide a line securing clamp which may be applied to boards of varying thickness without requiring adjustment or alteration of the clamping means.

A further object of this invention is to provide a clamping means which may also be secured to a flat surface, a wall or floor, or to timbers or other objects of substantial thickness.

Still another object of this invention is to provide a clamping device which is small, easy to apply, simple in its construction and relatively inexpensive in its cost of manufacture.

A further object of this invention is to provide a clamping device wherein means is provided for securing the line in taut condition by a simple and quickly performed operation.

Other objects of the invention reside in the details of construction and in the relationship of the various parts as will hereinafter be more fully described.

In accomplishing the above mentioned and other objects, I have provided the improved details of construction, the preferred forms of which are illustrated in the accompanying drawings—

Fig. 1 is a perspective view of a pair of line clamping devices applied to opposite ends of a

2

board and a chalk line drawn taut between and held at its ends by the clamping members.

Fig. 2 is an enlarged perspective view of the clamping device embodying the features of my invention.

Fig. 3 is a cross-sectional view taken on line 3—3 in Fig. 2.

Fig. 4 illustrates the manner in which the clamping device may be applied to a flat surface such as a wall or floor.

Fig. 5 illustrates the manner in which the clamping device may be applied to the end or side of a timber.

Referring more in detail to the drawings—

15 In Fig. 1, I have illustrated a board designated in its entirety by reference numeral 10 and comprising the side surfaces 10a, and the top surface 10c. The clamping means which embodies my invention is designated in its entirety by reference numeral 11 and, as is illustrated in Fig. 1, is designed primarily to be applied to a relatively thin board or sheet like material.

20 The clamping device is an integral unit formed from a single piece of relatively light gauge spring steel material. It comprises a base or bottom portion 12, and end wall 13 perpendicular to the bottom portion, and the top portion 14 extends at right angles to the end wall and is substantially parallel to the bottom. The top portion is divided along a central longitudinal line by a deep cut, V-shaped notch 15, into a pair of ears or flanges 14'—14', and it will be seen by reference to Fig. 2 that the inner end or apex of the notch extends into the end wall 13. The specific purpose or 25 reason for this construction will hereinafter be set forth.

30 To provide the clamping effect, I provide an upwardly extending and rearwardly curved clamping leg 20 which extends from the outer 35 end of the base 12 toward the end wall 13. This clamping member is rounded into a closed curl at its outer end as at 21 and terminates short of the end wall, and relatively close to the ears 14'—14' as noted in Fig. 3.

40 At the opposite ends of the end wall 13, I provide ears 22—22 which extend in the same vertical plane as the end wall. These ears preferably are rounded or curved on their edges as shown. Holes are provided in the ears, as at 23, and a 45 hole 24 is provided through the endwall 13 at a center point.

50 The preferred distance between the base 12 and top portion 14 is one and one-eighth inch, and the clamping member 20 provides that the device 55 may be applied to boards varying in thickness

from approximately one-eighth of an inch to one inch and it is applied by merely causing the end portion of the board to be received between the top portion 14 and the clamping leg 20. If the device is applied to a board which, for example, is three quarters of an inch in thickness, the clamping leg will be depressed or sprung downwardly to receive the board and will remain tightly clamped thereto.

As is illustrated in Fig. 1, a pair of clamping devices is used in combination, one clamping device being applied to each end of the board. The string or chalk line 30 is passed through the center hole 24 in the end wall 13 and a knot (not shown) is tied in the end of the line at the outer side of the end wall. The opposite end of the chalk line is drawn through the hole 24 in the opposing clamping device and is caused to be wound around the ear 22 as is illustrated in Fig. 1. With the chalk applied and the line drawn taut the carpenter may raise the chalk line and permit it to snap against the board in the conventional manner thereby providing a straight chalk line on the board.

In Figs. 4 and 5, respectively, I have illustrated the manner of application of the chalk line clamping device to a wall and timber. In Fig. 4 the device is applied to a wall 31 with the end wall 13 of the device flatly disposed against the wall surface and held in secured position by the application of nails or brads which are projected through the holes in ear 22-22. The line 30 is seated in the vertex of the V-shaped notch 15 and as previously stated, the V-shaped notch extends beyond the juncture of the top portion 14 and the end wall 13, thus permitting the chalk line to be stretched flatly against the wall. The line is chalked and the wall is caused to be marked in the same manner as indicated in marking a board.

The clamping device is applied to a timber or an object of substantial thickness as is illustrated in Fig. 5, by causing the end wall 13 to be flatly disposed against one end or side surface of the timber 32 and the device is then temporarily secured to the timber by means of nails through the holes in ears 22-22. The line is drawn tight as previously described and the chalk marking is applied to the timber in the conventional manner. As previously stated, this device may also be used in obtaining a straight line on a floor or other surface and it is readily seen that the clamping means may be applied in various ways for securing so as to hold the line taut and properly in position for making a line.

Though my device is designed primarily to be used to produce a chalk line marking, it is to be understood that it may also be employed to temporarily secure a small line for various uses, and to provide that the line may be readily removed when its use has been terminated. The size of the device and relative proportions in size of its parts may vary as desired or required and the specific shape may be altered without departing from the teaching of this invention.

Having thus described my invention, what I claim as new therein, and desire to secure by Letters Patent, is:

1. A chalk line clamp comprising a metal strip bent to form a bottom portion, an end wall, a top portion overlying said bottom portion and spaced therefrom, and a resilient clamping leg extending upwardly and rearwardly from the outer edge of the bottom portion; said end wall having a hole therein through which one end portion of the chalk line is passed, and ears projecting from the opposite ends of the end wall providing means about which the end of the line, after passing through the hole in the end wall, may be removably secured.

2. A combination as in claim 1 wherein the ears of the clamp are provided with holes therethrough to receive nails for the securement of the clamp to a wall.

3. A chalk line clamp of the character described comprising a single strip of relatively thin spring steel bent to form a bottom portion, an end wall extending at right angles to the bottom portion, a top portion extending at right angles to the end wall and overlying the bottom portion in spaced relationship therefrom, and a resilient clamping leg extending upwardly and rearwardly from the outer edge of the bottom portion toward said end wall, said top portion of the clamp having a V-shaped notch formed therein longitudinally thereof and having the apex thereof extending into the top edge portion of end wall, and said end wall having a hole therethrough directly below the apex of the notch to receive the end portions of a chalk line therethrough.

HENRY STODGELL.
